Primary Examiner — Robin V Webster(74) *Attorney, Agent, or Firm* — Keusey & Associates, P.C.(57) **CLAIM**

I claim the ornamental design for a paint tray, as shown and described.

DESCRIPTION

FIG. 1 is a top, front, left side perspective view of a paint tray assembled on a paint can.

FIG. 2 is a top plan view thereof.

FIG. 3 is a left side elevational view, the right side elevational view being a mirror image thereof.

FIG. 4 is a front side elevational view thereof.

FIG. 5 is a top, front, left side perspective view thereof; and, FIG. 6 is a bottom plan view thereof.

The dotted line representations of a paint container in FIG. 1 is included to show environmental structure and form no part of the claimed design.
